UNITED STATES PATENT OFFICE.

JOHN PATRICK HEDSTROM, OF BIG RAPIDS, MICHIGAN, ASSIGNOR TO HANCHETT SWAGE WORKS, OF BIG RAPIDS, MICHIGAN, A FIRM.

SAW-SHARPENING MACHINE.

No. 884,385.

Specification of Letters Patent.

Patented April 14, 1908.

Application filed January 22, 1907. Serial No. 353,508.

To all whom it may concern:

Be it known that I, JOHN PATRICK HEDSTROM, a citizen of the United States, residing at Big Rapids, in the county of Mecosta and State of Michigan, have invented certain new and useful Improvements in Saw-Sharpening Machines; and I do hereby declare the following to be a full, clear, and exact description of the invention, such as will enable others skilled in the art to which it appertains to make and use the same.

My invention relates to back feeding mechanism for saws, and while it may be applicable in connection with other saws, I have chosen to illustrate one embodiment of the invention as applied to the back feeding of band saws.

One object of my invention is the provision of means to relieve the direct feed of a portion of the work necessary to feed the saw forward step-by-step, thereby obtaining an easier and absolutely positive feed.

Another object is the provision of a back feeding mechanism having few parts of simple construction.

A further object is the provision of means for displacing a part at least of the mechanism while it is still attached to the saw sharpening machine, in order to obtain more space.

A still further object is the provision of a back feed mechanism which can be attached to any of the usual types of saw sharpening machines now on the market.

To these and other ends, therefore, my invention consists in certain novel features and combinations, such as will be more fully described hereinafter and particularly set forth in the claims.

In the accompanying drawings, Figure 1 is a perspective view illustrating the application of my invention to a saw sharpening machine; Fig. 2 is a view in side elevation of my invention and Fig. 3 is a top plan view thereof.

(A) indicates a saw sharpening machine of any suitable construction, equipped with the usual grinding wheel (B) and the oscillating feed bar (C) working in a slot (D) in the frame (E) of the machine. As the machine forms no part in this invention, further description thereof is unnecessary.

Secured to the oscillatory feed bar (C), is a hinge member, one leaf (1) of which is fastened to the bar, the remaining leaf being

formed into a pin (3) pivoted to the leaf (1), as at (4), the pin being of any suitable shape.

A lever (5) is pivoted, as at (6) intermediate its ends, preferably, to a bracket (7) secured to the frame (E) near the back of the machine, the lever extending across the machine and capable of a horizontal oscillation.

The forward end of the lever is loosely connected to the hinge joint, as by being socketed at (8) to receive the pin (3), which is adapted to telescope thereinto and move back and forth therein. Thus it will be seen that the lever (5) extends at approximately right angles to the path of oscillation of the feed bar (C), and as the feed bar moves back and forth it will cause the oscillation of the lever (5), the pin (3) moving in and out of the socket (8) by reason of the arc movement of the socketed end of the lever which does not correspond with the rectilinear oscillation of the feed bar.

The rear end of the lever is provided with an arm (9) horizontally pivoted thereto, the end of the lever carrying wings (10) (10) embracing the side edges of the arm to prevent lateral movement thereof relative to the lever. The extreme outer or rear end of the arm is provided with a finger (11) adjustably secured thereto in any convenient manner, as by means of the set screw (12), such finger adapted to take between adjacent teeth of a band saw, and as the lever is oscillated, such finger will impart a movement to the saw to assist the feed bar (C) in moving the saw step-by-step or tooth-by-tooth in position to be engaged by the grinding wheel (B).

The band saw is supported on the stands (F) in such manner as to encircle the machine. The feed bar and its connected parts engage that part of the saw passing in front of the machine, and the back feed finger (11) engages that part of the band saw passing behind the machine. As the feed bar moves forward to push the next tooth beneath the grinding wheel, the back feed finger will be moved in the opposite direction to assist the feed bar in moving the band saw step-by-step, the reverse movement of the feed bar causing the finger (11) to ride over the succeeding tooth and drop behind it in readiness for the next forward movement of the feed bar.

When it is not desired to use the back feed, the lever may be entirely disconnected from the bracket and the feed bar, or the arm may

be swung or folded over upon the lever to economize space.

It is obvious that the bent or offset bracket (7) may be dispensed with and the lever pivoted directly on the frame of the machine, if desired. The bracket is bent or offset to permit access to the pivot point of the lever.

Having thus fully disclosed my invention, what I claim as new is—

- 10 1. The combination with a band saw sharpening machine provided with an oscillatory feed member, of a lever pivotally supported midway of its length, the lever adapted to move in a horizontal plane, a suitable connection between one end of the lever and the feed member, and a saw tooth engaging pawl on the opposite end of the lever adapted to engage the return lead of the saw to assist the feed member in moving the saw step by step.
- 15 2. The combination with a band-saw sharpening machine provided with an oscillatory feed member, of a lever pivotally supported midway of its length, the lever adapt-

ed to move in a horizontal plane, a suitable 25 connection between one end of the lever and the feed member, and a saw-tooth engaging the pawl on the opposite end of the lever, the pawl hinged to the lever to move vertically and laterally immovable relative to the lever. 30

3. A connection for two operative elements moving in planes transverse to each other comprising a telescoping pin hinge-secured to one of the levers, the remaining lever provided with a socket in which the 35 pin is loosely received.

4. A connection for two movable elements comprising a hinge, one leaf of which is secured to one of the elements, a pin on the remaining leaf of the hinge, the remaining element having a socket for loosely receiving the pin. 40

In testimony whereof, I affix my signature in presence of two witnesses.

JOHN PATRICK HEDSTROM.
